UNITED STATES PATENT OFFICE

DONALD WILFRED SESSIONS, OF FINCHLEY, LONDON, ENGLAND

LIFTING JACK

Application filed August 4, 1930, Serial No. 472,912, and in Great Britain October 15, 1929.

This invention relates to lifting jacks.

According to the invention a lifting jack has incorporated therewith a casing comprising separable portions adapted to be moved into co-operation to enclose the jack when the latter is collapsed. The casing preferably comprises a container within which the collapsed jack is housed and a lid member or members secured to the jack and adapted to be moved thereby to form a closure to the container when the jack is collapsed. In applying the invention to a jack of the kind comprising two sets of four bars arranged in the form of a lazy tongs or toggles device (adjacent bars acting as toggle levers) and a screw device for moving the pairs of outer ends of the bars towards or away from each other, a lid member may be secured to the corresponding lower bars of adjacent sets thereof. The inner ends of the lower bars may be attached to a common member having a casing secured thereto with which the lid members co-operate to form a closure to the container.

In order that the said invention may be clearly understood and readily carried into effect the same will now be described more fully with reference to the accompanying drawings, in which:—

Figure 1 is a view of a jack casing constructed in accordance with the invention, the left half being in longitudinal section and the right half in side elevation.

Figure 2 is a plan view thereof, the left half being a top plan and the right half a bottom or under plan.

Figure 3 is an end view, the right half of which is in longitudinal section.

Figure 4 is a side elevation of the jack in the open condition, and

Figures 5, 6, 7 and 8 are details to be described.

The container A is suitably shaped to enclose the jack and is adapted to be closed by a central pressing B and lid members C, C¹. The jack comprises two sets of four bars (one set only being illustrated in Figure 4), the pairs of upper bars D, D¹, being pivoted at d, d¹, respectively to a horizontal anchor plate E to which the container A is secured

by screws (not shown) passing through apertures a in the container. The outer ends of the bars D, D¹, are mounted on pivot studs d², d⁴, carried by blocks F, F¹. The outer ends of the pairs of lower bars G, G¹ are also mounted on the studs d³, d⁵ and their inner ends are pivoted to a base member G³ to which the central pressing B is secured by means of a plate G⁵ for resting on the ground which plate is provided with a threaded stem G⁴ that passes through an aperture B¹ in the pressing B and screws into the base member G³. The plate G⁵ can be removed for substitution of a deeper plate or a distance piece. The lid members C, C¹, are bolted or riveted to horizontally disposed lugs provided on the lower sides of the bars G, G¹, respectively, and their side marginal portions C² are bent upwards and extend into proximity to projections C³ formed by pressing inwards a portion of the container A at each side thereof. This arrangement assists in preventing ingress of water and dirt into the interior of the casing and serves to render the sides of the case rigid and stiff. For these purposes also the outer ends C⁴ of the lid members are bent upwards and their inner ends C⁵ are bent downwards and slide over and in contact with the rounded ends of the pressing B. The inner ends of the bars are formed with toothed bosses, the teeth of the upper bars, and of the lower bars, of each set intermeshing so that equal and opposite movement of the bars is ensured. The teeth of the upper bars mesh with those of the lower bars when the jack is collapsed thereby facilitating collapse of the jack to a small height. Corresponding pairs of the upper bars are secured together by studs D⁴ so that movement of the bars in unison is ensured and so that they are rendered more rigid. The studs D⁴ are secured to projections or bosses D⁶ on the bars so that the studs do not interfere with the complete collapsing movement of the upper and lower bars. The ends of the plate E are extended transversely over the bars D, D¹, and between these transverse ends the plate E is located between the two sets of bars; the bars D, D¹, are shaped to avoid their contacting with the transverse

ends of the plate so as to permit complete collapse of the jack. By this arrangement the upper surface of the plate E does not extend substantially above the bars D, D¹, and the jack when collapsed occupies a small space vertically thereby enabling the container A to be small and of neat appearance. The container A is formed with two longitudinal slots A¹ through which the heads of T-shaped bolts E⁵ can be inserted into corresponding slots E¹ in the plate E, the slots E¹ being of inverted T-shaped cross-section so that when the heads of the bolts E⁵ (see Figure 6) are inserted therein and rotated the heads will be anchored in the plate E. Means supported by the axle, spring, or other suitable part of the vehicle, are provided to which the bolts E⁵ are secured. One form of such means is illustrated in Figures 5 and 6 and comprises two angular members or plates K of T-shaped end view each having a lower horizontal limb k and upper limbs k¹ inclined to the horizontal so that their outer ends are lower than their inner ends. The limbs k are clamped firmly to the plate E by the bolts E⁵, the slots A¹, E¹, permitting adjustment of the bolts transversely of the jack. Supporting bolts k² pass through slots in the limbs k¹ and through slots in corresponding limbs k³ of a plate K¹ located above the spring J. The limbs k³ are inclined upwardly, i. e. in the opposite direction to the limbs k¹, so that when nuts k⁴ are screwed home on the bolts k² the latter will slip towards each other and grip the spring J. In order that the bolts may move easily down the inclined limbs k¹, k³, the latter are recessed, and the bolt heads are rounded as shown, and round-washers k⁵ are provided at their opposite ends. This arrangement is particularly suitable for attaching the jack to a rear axle spring as it provides a clearance for the spring bolts k⁶. For securing the jack to the front axle the container A is provided at each end with two transverse slots A⁷ and the transverse ends of the horizontal plate E are provided with corresponding slots or grooves E⁷ of similar cross-sectional shape to the slots E¹. The supporting bolts k² depending from the plate k¹ located above the axle J¹ are formed with rectangular heads k⁸ to be engaged in the slots E⁷ (see Figure 7). The surfaces of the slots E⁷ that are engaged by the bolt heads are inclined so that the bolts slip towards each other when they are tightened. If the jack is secured to the centre of an axle a jaw M (see Figures 7 and 8) may be provided at each side of the centre between the container A and the axle J¹, the upper surfaces of the jaw being serrated, V-shaped in end view, curved longitudinally of the jack, or otherwise suitably formed to ensure a firm bedding of the axle thereon. The jaws are formed with downwardly projecting studs or tongues m engaged in the slots

E¹. Located centrally through the jack is a spindle P comprising a plurality of telescopic parts and having right and left threaded portions that are screwed through threaded apertures in the blocks F, F¹, respectively, so that when the spindle is rotated the blocks F, F¹, and consequently also the pairs of outer ends of the bars, will be moved towards or away from each other thus opening or collapsing the jack. The left hand end (Figure 1) of the container A is suitably shaped at A⁸ to receive one end of the spindle and the right hand end is similarly shaped and provided with a slot A⁴ through which the other end of the spindle passes. Suitable provision may be made for preventing undesirable rotation of the spindle P due for example to vibration whilst the vehicle is in motion. These means may comprise spring washers N which are compressed between washers N¹ adapted to be moved apart by the blocks F, F¹, and shoulders or collars N² on the spindle P, when the jack is collapsed, or may comprise a weighted lever. The outer end (not shown) of the screw spindle is suitably shaped to engage in a socket in a device for rotating it.

What I claim and desire to secure by Letters Patent of the United States is:—

1. A lifting jack comprising two sets of four bars arranged side by side and pivoted together to form a toggles device, a screw device for moving the pairs of outer ends of the bars towards or away from each other, a casing secured to the jack and adapted to contain the jack when collapsed, and a lid member secured to each of two pairs of corresponding bars so that when the jack is collapsed said bars move the lid members to form a closure to the casing.

2. A lifting jack according to claim 1, in which a lid member is secured to the jack between the lid members that are secured to the bars.

3. A lifting jack comprising two sets of four bars each located side by side and pivoted together to form a toggles device, a screw device operatively connected with said bars, a casing secured to the device above the upper ends thereof and adapted to contain the collapsed jack, a middle lid member secured to the inner ends of the lower bars, and a lid member secured to each pair of corresponding lower bars, all the lid members being moved into co-operation to form a closure to the casing when the jack is collapsed.

4. A lifting jack comprising a horizontal plate forming an anchorage for bolts whereby the jack is attached to a motor car, two sets of four bars one set on each side of the horizontal plate and pivoted together to form a quadrilateral toggles device the inner ends of the upper bars of which are pivoted to said horizontal plate, a screw device for operating the toggles device, a member for rest-

ing on the ground to which the inner ends of the lower bars are pivoted, a container having a top secured above the horizontal plate and side walls extending downwardly, and
5 adapted to contain the toggles and screw devices when the jack is collapsed, a lid member secured to the member for resting on the ground, and a lid member secured to each pair of corresponding bars of the two sets,
10 said lid members being all moved into co-operation by the toggles device when the latter is collapsed to form a closure to the container.

5. A lifting jack as in claim 1, wherein the
15 top of the casing is provided with solts to receive the heads of bolts whereby the jack is secured to a part of a motor car and with an aperture to receive a downwardly extending projection on a block adapted to engage
20 said part.

6. A lifting jack comprising toggle bars, means to open and collapse said bars, two members secured to the lower toggle bars so as at all times to be parallel to the bars to
25 which they are attached, means attached to the jack and adapted to cooperate with said two members when the jack is collapsed to form a casing enclosing the jack.

7. A lifting jack comprising two sets of
30 four bars arranged side by side and pivoted together to form a toggles device, a screw device for moving the pairs of outer ends of bars towards or away from each other, two members secured one to each pair of corresponding lower bars in the two sets so as at all times to be parallel to the bars to which they are attached, and means attached to the jack and adapted to co-operate with said two members when the jack is collapsed to form
35 a casing enclosing the jack.

8. A lifting jack comprising two sets of four bars arranged side by side to form a toggles device the lower ends of all the lower bars being permanently adjacent to each
45 other, a container attached to the upper bars and adapted to contain substantially the whole of the bars when the jack is collapsed, and two lid members secured one to each pair of corresponding lower bars in the two sets so as at all times to be parallel to the bars to which they are attached, the arrangement being such that when the jack is collapsed the bars move the lid members to form a closure to the container.

50 55 DONALD WILFRED SESSIONS.
